COMBINED NUT PICKER AND SHELL CRACKER

Vincent G. Brunderman, 1725 N. 1st Ave.,
Metrose Park, Ill. 60160

Filed Jan. 25, 1967, Ser. No. 5,562

Term of patent 14 years

(Cl. D44—1)

FIG. 1 is a perspective view of a combined nut picker and shell cracker showing my new design;

FIG. 2 is a front elevational view;

FIG. 3 is a top plan view;

FIG. 4 is a bottom plan view;

FIG. 5 is an end elevational view thereof, taken from the left of FIGS. 1 and 2, and

FIG. 6 is an end elevational view thereof, taken from the right of FIGS. 1 and 2.

I claim:

The ornamental design for a combined nut picker and shell cracker, as shown.
